UNITED STATES PATENT OFFICE.

ALBERT J. LARM, OF HAGERSTOWN, MARYLAND.

CURLING IRON.

Application filed July 3, 1924. Serial No. 724,051.

To all whom it may concern:

Be it known that I, ALBERT J. LARM, a citizen of Germany, residing at Hagerstown, in the county of Washington and 5 State of Maryland, have invented certain new and useful Improvements in Curling Irons, of which the following is a specification.

This invention relates to improvements in 10 curling irons and has for an important object thereof the provision of a device of this character retaining its heat for a greater length of time than the ordinary construction of curling iron, and which at the same 15 time is of such construction that burning of the hair during the curling operation is avoided.

A further object of the invention is to 20 provide a curling iron having the usual co-acting members for grasping the hair between, one of which is grooved and the other of which is in the form of a body adapted to fit into the groove in which this body is formed in two separable sections, one 25 of which is hollow and contains a metal retaining heat for a considerable period of time.

These and other objects I attain by the 30 construction shown in the accompanying drawings, wherein for the purpose of illustration is shown a preferred embodiment 35 of my invention and wherein:—

Figure 1 is a perspective view of a curling iron constructed in accordance with my invention;

Figure 2 is a vertical sectional view 35 through one section of the iron;

Figure 3 is a perspective of the heat retaining rod removed.

Referring now more particularly to the 40 drawings, the numerals 10 and 11 indicate a pair of plier connected members pivoted to one another, as at 12. These plier members each embody a body portion and a handle portion, the body portion of the member 11 being formed in two sections 13 and 45 14. The section 13 is integral with the handle portion of the member 11 and is provided with a reduced threaded extension 15. The section 14 is in the form of a tube 50 having its outer end closed and its inner end interiorly screw-threaded for coaction with the threaded extension 15 of the section 13. The walls of the tube 14 are provided with radial perforations 16, and 55 movably located within the bore of the tube is a rod 17 of greater thermo capacity than

the material from which the tube 14 is formed, that is to say, this rod has the quality of retaining heat for a greater length of time than the material from which the tube 60 is formed, as, for example, the tube may be formed from steel and the rod formed from copper or bronze. The coacting section of the other plier member 10 is of the usual construction, having a groove 18 for the reception of the tube as is usual.

In the use of the device, the plier members are heated in the usual manner and the outer shell of the tube 14, being relatively thin, cools rapidly and accordingly is extremely unlikely to be sufficiently hot to scorch the hair at any time during the curling operation. During the curling operation the rod 17 gives off its heat which passes through the openings 16 of the tube 70 to the hair, drying the same to set the curl in the usual manner. If it is desired that the handles of the plier members be formed integrally with the operating or jaw ends thereof, these handle members are preferably provided adjacent the pivot thereof with a plurality of centrally disposed, longitudinally spaced openings 19 through which air can circulate to prevent the passage of heat from the jaw ends to the handle ends.

Among the advantages of my device may be mentioned the fact that, as is well known, in heating curling irons for waving hair, the grooved members becomes very much 90 hotter than the other body member because it of necessity is of smaller metallic content and burning of the hair is usually caused by the grooved member being so hot. With my device, however, the heat is retained in the body member in such manner that it comes in contact with the hair only by radiation and in view of the fact that the heat is retained in the body member by employing greater thermo capacity 100 than the grooved member, the latter is not heated to such an extent that there is liability to burn the hair in the practical use of the device.

Since the device is capable of a certain 105 range of change and modification without materially departing from the spirit of my invention, I do not limit myself to such specific structure as hereinbefore set forth except as hereinafter claimed.

I claim:—

1. In a curling iron, a pair of plier con-

nected members having handle ends and operating ends, the operating end of one of said members having a groove receiving the other of the members, the other operating 5 end being formed in two separable sections, one of which is provided with a longitudinally extending bore and has formed in its side wall radially directed openings, a bar of heat retaining material freely mounted 10 within said section and removable therefrom upon separation of the sections.

2. In a curling iron, a pair of plier connected members having handle ends and operating ends, the operating end of one of 15 said members having a groove receiving the

other of the members, the other operating end being formed in two separable sections, one of which is provided with a longitudinally extending bore and has formed in its side wall radially directed openings, a bar of 20 heat retaining material freely mounted within said section and removable therefrom upon separation of the sections, the handle sections of said members being provided adjacent the pivots thereof with a plurality of 25 centrally disposed openings preventing the transmission of heat from the operating ends to the handle ends.

In testimony whereof I affix my signature.
ALBERT J. LARM.
